COMMODE OR THE LIKE

David P. Zagarioli, 2035 11th Street Court NW,
Hickory, N.C. 28601

Filed Apr. 16, 1975, Ser. No. 568,507

Term of patent 14 years

Int. Cl. D6—04

U.S. Cl. D6—158

The figure is a front perspective view of the commode or the like showing my new design.

The opposite side of the commode is substantially a mirror image of that shown.

The back and bottom of the commode are substantially plain and unornamented.

I claim:

The ornamental design for a commode or the like, as shown and described.
